FIG. 1 is a front perspective view of an electronic instrument enclosure and cover therefor, showing our new design;

FIG. 2 is a rear, perspective view of the enclosure of FIG. 1, the front cover being omitted;

FIG. 3 is a front view of the enclosure of FIG. 1, the front cover being omitted;

FIG. 4 is a side view of the enclosure of FIG. 1, the front cover being omitted;

FIG. 5 is a top view of the enclosure of FIG. 1, the front cover being omitted;

FIG. 6 is a top, perspective view of the enclosure of FIG. 1, including a front cover member extending between the handles thereof;

FIG. 7 is a front, perspective view of the enclosure of FIG. 1 with the handles and front cover removed;

FIG. 8 is a side view of the enclosure of FIG. 7;

FIG. 9 is a top view of the enclosure of FIG. 7; and

FIG. 10 is a perspective view of the front cover of the electronic instrument enclosure.

The characteristic feature of the design resides in the front cover of the electronic instrument enclosure as seen in FIGS. 1, 6 and 10.

We claim:

The ornamental design for an electronic instrument enclosure and cover therefor, as shown and described.
